UNITED STATES PATENT OFFICE.

JOSEPH DOVE-SMITH, OF NIAGARA FALLS, NEW YORK, ASSIGNOR TO JACOB F. SMITH
PAPER BOX COMPANY, INCORPORATED, OF BUFFALO, NEW YORK.

BOX-LABELING MACHINE.

1,158,651.

Specification of Letters Patent. Patented Nov. 2, 1915.

Substitute for application Serial No. 724,833, filed October 9, 1912. This application filed March 1, 1915.
Serial No. 11,434.

To all whom it may concern:

Be it known that I, JOSEPH DOVE-SMITH, a subject of the King of Great Britain, residing at Niagara Falls, in the county of 5 Niagara, State of New York, have invented new and useful Improvements in Box-Labeling Machines, of which the following is a specification.

My invention relates to box labeling machines, and more particularly to machines for doming and automatically applying labels to boxes, such as ordinary paper or pulp boxes.

This application is a substitute for my 15 former application Serial No. 724,833, filed October 9, 1912.

The object of my invention is to incorporate in the machines in common use certain improvements which will be specifically 20 described, and to dome the boxes in connection with the labeling process.

It is old and common practice to feed boxes or other similar objects, such as cartons or bottles, into a machine which holds 25 the article, gums or glues a surface, supplies a label to the gummed surface, presses the label down, and removes the article thus labeled from the machine. This is done by a step-by-step movement over a circle or in 30 a straight line. My machine employs several of these old and general means and adds thereto certain specific improvements. While 35 I shall describe my improved mechanism for pressing down and securely affixing a label to a box in combination with the other improvements herein described and claimed, said mechanism is more specifically described and claimed in my application filed Nov. 5, 1913, Serial No. 799,299.

40 Referring to the drawings herewith which form a part of this specification, Figure 1 is a top plan view. Fig. 2 is a longitudinal, central, vertical section. Fig. 3 is a transverse central, vertical section. Fig. 4 is a detail of the well-known Geneva wheel employed to produce the step-by-step movement. Fig. 5 is a plan of the actuating gearing and cams. Figs. 6, 7, 8, and 9 are, respectively, a side elevation, longitudinal section, end view and plan of my box holding device. Figs. 10 and 11 are, respectively, detail longitudinal and transverse sections 45 of my domer. Fig. 12 is a detail of the

gluing mechanism, and Figs. 13 and 14 are, respectively, a detail section and an under- 55 side view of my affixing mechanism. The drawings are in part diagrammatic, non-essentials and perspectives being omitted for clearness.

Figs. 1 to 5, inclusive, show the mechanism which for the most part is old, used in connection with my improvements, and the remaining figures illustrate my improvements particularly. I will, therefore, describe briefly the general mechanism, and 60 then point out my improvements in detail.

A rotor 1 is mounted to revolve step-by-step upon a fixed table 2, and is driven by a Geneva wheel 3 secured to the under side of the rotor, and a cam-crank 4 on a shaft 5 70 driven by bevel gears 6 and 7 from a shaft 8, which takes its power through bevel gears 9 and 10, shaft 11, gears 12 and 13, shaft 14 and belt pulley 15.

Boxes, or box covers or box bottoms, are 75 stacked in the magazine 22 by an operative. A reciprocating plate 23, the face of which is somewhat smaller than the side or end of the box against which it bears, pushes the lowermost box out of the magazine 22 onto 80 a box holder on the rotor hereafter described. This plate 23 is reciprocated by an arm 24 actuated by a crank 25 connected to a rod 26 which is actuated by a cam 27 on the shaft 11. 85

It will be understood that the shafts 11 and 8, the shaft 16 through the bevel gears 9 and 21, and the shaft 17 through bevel gears 18 and 19 are in constant rotation.

Assuming a box to have been put in place 90 upon one of the box holders, the Geneva wheel now moves the rotor one step and brings the box in position for the domer to act. This consists in general (the details hereafter described) of a fixed plate 95 28, concaved on its under side to conform to the curvature or doming desired, means for heating the plate, and a plunger 29, convexed to the desired curvature and carried by the rotor, between which and said plate 100 28 the box is pressed. The plunger 29 is actuated by a follower 30 which is reciprocated by a cam 31 on the shaft 16. The step-by-step mechanism now moves the box to the gluing position, where a follower 105 32 which is actuated by a cam 34 on the shaft

16 acts on the plunger 29 and raises the box to a position where a glue-pad 33 may apply glue to its surface as hereafter described in detail. The rotor now moves the box coated with glue or paste under the label magazine 35. This magazine is the familiar device containing a stack of labels held peripherally so that the bottom label may be drawn out by suction. The plunger 29 raises the box into contact with the bottom label in the magazine and the adhesion of the glue carries the label down on the top of the box. The plunger 29 is here actuated by a follower 36 actuated by the cam 31 through the bell-crank lever 37 (Fig. 5). The rotor now moves the box to the pressing or affixing mechanism, which consists generally of a pressure-pad 38 against which the plunger 29 presses the label and box. The plunger 29 is here actuated by the follower 39 which is actuated by the cam 40 on the shaft 8. In order to insure perfect contact and smoothness, the box is now passed under a second pressure-pad, identical with the pad 38, and in this position the plunger 29 is actuated by a follower 41 reciprocated by the cam 42 on the shaft 8 through a bell-crank lever 43. The rotor now moves the box into position to be ejected. This is accomplished by a pneumatic device, hereafter described, which is actuated by the lever 44 and cam 45 on the shaft 8.

Having described a cycle of operations generally, I will now describe my improvements.

Referring especially to Figs. 6 to 8, I will first describe the box-holding mechanism. The rotor has the upwardly-extending cylindrical portions 45, each of which carries within it a plunger 29. To each of these cylindrical portions is clamped a box-holder of the following construction. Each clamp 46 has upwardly-turned end-plates 47. Reciprocatingly secured by pins 48 in slots in these end-plates are plates 49. These plates 49 have internal flanges 50, upon which rest out-turned flanges 51 on plates 52 which are rigidly secured to the plungers 29. Hinged to the plates 49 are plates 53. These plates 53 have cylindrically-formed beads 54, formed upon their upper edges, which bear against the outsides (ends or sides as the case may be) of the boxes 55 when in place. The ends of these beads are chamfered adjacent to the feeding device, as shown at 56 in Fig. 9, to permit the shoving in of the box by the feeder. Light springs 60 (Figs. 6 and 7) hold the plates 53 up against the box. The convexed heads of the plungers 29 are of a size to move freely in or out of the boxes without contacting the inner side walls. Projecting inwardly on the plates 49 and adjacent to the hinges are shoulders 61 which lie above and

in the path of the flanges 51 on the plates 52. Threaded into the bottoms of the plates 49 are pins 62 having heads 63, which heads slide within tubular sleeves 64 which are rigidly secured to the clamps 46. Within the sleeves 64 and bearing against the heads 63 and the clamps 46 are compression springs 65.

The operation is as follows: The plunger 23 shoves the lowermost box from the magazine 22 in between the chamfered ends 56 of the beads 54, and the said beads, held up by the springs 60, thus clamp and hold the box throughout the several operations. The rotor now carries the box thus in place under the domer. The follower 30 raises the plunger 29 into the interior of the box, and the flanges 51 contact with the shoulders 61 on the plates 49, thus lifting the plates 49, hinged plates 53 and the boxes 55 up and into contact with the underside of the domer 28, and the continued action of the cam operating the follower 30 applies sufficient pressure to perform the necessary doming. When the cam permits the follower 30 to 90 retract, the plunger 29 and the parts carried by it as above described return to their initial position; and to insure this return, the said springs 65 acting on the pins 62 force the plates 49 back onto their seats, where they are thereafter firmly held by the flanges 51 on the plates 52 resting upon the flanges 50. It will thus be seen that the plunger action is positive and must always be in proper alignment; that the box is continuously held in its proper position; and that the movement of the box in and out of contact with the overhanging parts is direct and positive.

The domer consists of the plate 28 which is rigidly supported upon the table 2 at its outer end, and at its inner end upon a table 66 which is rigidly mounted upon the table 2, as clearly shown in Figs. 2 and 3. Upon the under side of this plate 28 is a concaved portion 67, conformable to the convexed surface of the plungers 29, and upon the upper surface of the plate 28 is a hood 68, adjacent to one end of which is the nozzle 69 of a Bunsen burner, or other heating means, for heating the plate 28 and the projection 67. It is evident that, when a box is forced up against this concave, heated surface by the plunger 29 which has a correspondingly curved surface, and considerable pressure is applied, the box will be domed or bulged on its top to give it a more attractive appearance.

The gluing or glue-applying process is effected as follows: The glue-pad 33 is 125 mounted to reciprocate in a frame 70 by means of an arm 71, actuated meditately by the cam 72 on the shaft 17. The glue-pad is carried resiliently in a carriage 73 by means of studs 74 and springs 75. In its 130

retracted position it moves over and in contact with a glue-applying roller 76 which is in contact with a second roller 77 which takes glue from a glue reservoir 78. These 5 rollers may be positively driven in the usual manner. When the lever arm 71 moves the carriage 73 into the glue-applying position over the box 55, an adjustable stud 79 carried in a yoke 80 which is carried by reciprocating rods 81 moves down into contact with the stud 82 on the glue-pad 33 and forces the glue-pad down onto the surface of the box 55. The rods 81 are reciprocated by a 10 cross-bar 82 which engages with a cam 83 on the shaft 16. In order to prevent the improper application of glue to the surface of a plunger 29 in case no box is in position, the following means are employed: Pivoted to the frame 70 is a rocking arm 84 which carries upon its lower end a roller 85 which bears against the side of a box, if there is a box in place. The upper end of this lever passes freely within an opening 86 in the yoke 80, provided a box is in position; but 15 if there is no box in position, a light spring 87 will rock said lever 84 so that its upper end will not be in alignment with the opening in the yoke 80, but will come in contact with the under side of said yoke and prevent the stud 79 from pressing down the stud 82 to bring the glue-pad in contact with a plunger when no box is present.

Referring now to the pressing mechanism separately described and claimed in my said 35 application Serial No. 799,299 shown in Figs. 3, 13 and 14, mounted over the line of travel of the plungers is a plate 88 which is rigidly supported upon the table 2 and the central plate 66. Secured to a projection 40 upon the under side of this plate is a rubber or other resilient pad 38, which is of a size to completely cover the label, which has a rectangular slot 89, clearly shown in Figs. 13 and 14, and within the boundaries of this 45 slot the bearing surface of the pad is a trifle above the bearing surface external thereto. This forms a sort of air chamber within the portion of the pad internal to the slot and also causes the pad, when thoroughly pressed down, to conform more closely to the convex surface of the label and box. Leading into this rectangular slot are air 50 openings 90. These air openings connect with a central valve 91 the head of which is in an air supply chamber 92. A supply of compressed air is carried to this chamber, as by a coupling 93 shown in Fig. 13. The bottom of the stem of the valve 91, when the valve is in the closed position, lies below the pressing surface of the pad 38, so that when the plunger raises a box into contact with said pad, it will press the stem of said valve upwardly, open the valve, and permit air to pass down through the openings 90 55 into the rectangular slot 89, be spread out

over the central portion of the label, and be forced out over the edges of the label to smooth it and press it down. This action of the air will press down and smooth out the label; but preferably, to insure perfect adhesion, I provide a second pressing device 70 identical with that just described which acts upon the label at the next step of the rotor, and which need not be described further than to note that, as shown in Fig. 1, both of 75 these pressers are supplied with air from a pipe 94 provided with a T 95, which source of air supply also actuates the ejector which I will not describe.

Mounted upon the central plate 66 is an 80 air-valve 96 which is supplied with air through a pipe 97 connecting with the T 95, and a pipe 98 leads from this valve to an air blast chamber 99, from which small pipes 100 lead and are positioned so as to 85 discharge blasts of air against the adjacent side of a box. The stem of the valve 96 is acted upon by the lever 44, which is actuated by the cam 45, as above described. When this valve is opened the blasts of air will 90 force the box horizontally out from between the contacting cylindrical edges 54 of the plates 53 into the tray or chute 101, from which the completely domed and labeled boxes may be carried to any desired position 95 without further manual handling, since they lie in uniform positions to be carried by an endless belt or a chute to the next point of operation.

It will be noted that in Fig. 1 a plate or 100 cover marked "Blank" lies between the ejector and the feed. No operation is performed at this point with the construction described; but the plunger and box carrier are preferably covered at this point as a protection to the operator sitting adjacent to it to place boxes in the feed magazine.

Having thus described my invention, I claim:

1. The combination with a rotor and 110 means for moving the same step by step, a plurality of projections thereon for carrying plungers, plungers in said projections, box-holding devices reciprocatingly secured to said projections, lifting means secured 115 to said plungers for engaging with said box-holding devices, followers for acting upon said plungers, mechanism for actuating said plungers, and superposed devices for engaging with said plungers to act upon a box. 120

2. In combination with a rotor and 125 means for moving the same step by step, a feeding mechanism for feeding in boxes, a plurality of projections on said rotor, plungers in said projections, box-holding devices secured to said projections comprising hinged plates for engaging the external sides of boxes, springs for holding said plates up into action, vertically sliding plates for raising said hinged plates engag- 130

ing the boxes, and means for lifting said sliding plates simultaneously with the entry of the plunger into the box.

3. In combination with a rotor and reciprocating plungers of the character describer, projections on said rotor, plates for holding boxes on their opposite ends or sides carried by said projections, means for lifting the box-holding plates into position coincidently with the action of the plunger, and means for positively returning said box-holding plates after each operation.

4. In combination with a rotor and a feeding device for feeding boxes into a box-holding device, box-holding devices carried by said rotor comprising yokes secured to projections on said rotor, plates carried by said yokes and plates hinged to said first-mentioned plates having engaging edges for engaging the sides of a box and said sides being beveled to permit the entrance of a box, and springs for holding said engaging plates against a box, said plates being arranged to engage a box externally upon its sides or ends.

5. In combination with a rotor, box carriers, plungers and means for actuating said plungers, a doming device comprising a plate rigidly mounted over the plunger path having a concave surface on its under side of the desired dome curvature, a device for bearing said plate, plungers having corresponding convex surfaces, whereby the box is pressed between said plate and said plunger to give it the domed or curved surface desired.

6. In combination with a rotor having a step by step movement, box-holding devices

for holding boxes rigidly against independent horizontal movement but permitting vertical movement of the boxes, plungers carried by said rotor and fitting within the boxes, followers for raising said plungers and means for actuating said followers and rigid overhanging plates to contact with the boxes when the same are forced upwardly by said plungers.

7. In combination with a box-carrying member having a step by step movement, box-holding devices mounted thereon arranged to reciprocate vertically but holding the boxes against independent movement, reciprocating plungers carried by said box-carrying member having heads conformed to the interior of the boxes to move freely therein, followers actuating said plungers, and rigid overhanging plates to contact with the upper and outer surfaces of the boxes when the same are raised by said plungers.

8. In combination with a rotor and plungers carried in projections on said rotor and means for actuating said plungers, fixed overhanging members positioned to coact with said plungers to act upon a box, and a box-carrying device in connection with each plunger and carried by said rotor, said box-carrying device engaging the box exteriorly and being reciprocatingly secured to said rotor whereby it may be raised by the plunger simultaneously with the box and returned to normal position when the plunger returns to its normal position.

JOSEPH DOVE-SMITH.
